UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A LAMP-FOUNT HOLDER.

SPECIFICATION forming part of Design No. 20,867, dated June 30, 1891.

Application filed June 1, 1891. Serial No. 394,763. Term of patent 14 years.

To all whom it may concern:

Be it known that I, ALBERT PATITZ, of Meriden, in the county of New Haven and State of Connecticut, have invented a new Design 5 for a Lamp-Fount Holder, (Case D;) and I do hereby declare the following, when taken in connection with accompanying drawing and the letters of reference marked thereon, to be a full, clear, and exact description of the 10 same, and which said drawing constitutes part of this specification and represents a perspective view of the holder.

This invention relates to a design for that 15 part of a standard lamp within which the removable fount is placed, commonly called the "fount-holder."

In outline the holder is of spherical shape—that is, starting from the bottom, expands by

an outward curve, which toward the top is turned inward, giving it the spherical shape. 20 The surface of the holder is ornamented by a tracery representing flowers, leaves, and branches, as shown in the accompanying illustration.

I claim—

The design for a lamp-fount holder, as herein described, and shown in the accompanying illustration.

In testimony whereof I have signed this specification in the presence of two subscribing witnesses.

ALBERT PATITZ.

Witnesses:
